UNITED STATES PATENT OFFICE

HENRIETTA PORR MANVILLE, OF NEW HAVEN, CONNECTICUT, ASSIGNOR TO THE GOODYEAR'S INDIA RUBBER GLOVE MFG. CO., OF NAUGATUCK, CONNECTICUT, A CORPORATION OF CONNECTICUT

SANDAL

Application filed July 11, 1931. Serial No. 550,084.

My present invention relates to sandals and more particularly to an improved bathing sandal.

The ordinary bathing sandal is objectionable in that it has too much structure on top of the sole and heel with the result that it is too heavy to wear while swimming and when worn out of the water does not afford sufficient ventilation for the feet.

10 My present invention obviates the objections above noted and in carrying out my invention, I have utilized a combined sole and heel, preferably made of resilient material and cork and utilize cord for defining the 15 toe of the sandal as well as the heel therefore, and also utilize a cord which is slidably connected to both the toe and heel members and acts as a means for attaching the sandal to the foot of the wearer.

20 The object of my invention, therefore, is an improved bathing sandal.

In the accompanying drawing, the figure is a perspective view of my improved bathing sandal.

25 Referring to the drawing, 10 designates a combined toe and heel member constructed of preferably a resilient material such as rubber and ground cork or other light weight material. The combined sole and 30 heel member 10 is formed of a toe portion 11 and a heel portion 12, connected together by an instep portion 13 and to the under face of the heel portion 12 is adhesively attached a low heel 14 of usual construction.

35 To the upper surface of the combined sole and heel member 10 is adhesively attached what may be termed an insole 15. This insole extends over the entire upper surface of the combined sole and heel member 10.

40 Adjacent to the rear end of the heel portion 12 and on either side of the longitudinal axis of the member 10 is secured, in any desirable way as by cement, the ends of a cord 16 that constitutes a heel loop and 45 which, when the sandal is in position on the foot of the wearer, as shown in the drawing, engages with the heel of the wearer. The ends of the heel loop 16 are preferably concealed from view by the insole 15. 17

50 designates a ring preferably of resilient ma-

terial, such as rubber, and 18 designates a toe loop, the ends of the toe loop 18 being secured to the toe portion 11 of the combined sole and heel member 10 and such loop is also threaded through the ring 11 as 55 clearly shown in the figure. 19 designates a toe loop similar in all respects to the toe loop 18 and this loop 19 is also threaded through the ring 17. 20 designates a side loop, the ends of which are secured to the toe portion 11 of the combined sole and heel member 10 and this loop also is threaded through the ring 17 as shown in the drawing. 21 designates a side loop on the opposite side of the structure from the side loop 20 and this side loop 21 is also threaded through the ring 17 and is similar in all respects to the side loop 20. 22 designates a tie cord, one end of which is secured to the instep portion 13 of the combined sole 70 and heel member 10 and this cord is then threaded through the ring 17 and through the heel loop 16. 23 designates a tie cord similar to the tie cord 22 and which is attached to the instep portion 13 on the opposite side of the structure from the cord 22. This tie cord 23 is also threaded through the ring 17 and through the heel loop 16. With 75 the foot of the wearer in position on the sandal, as shown in the drawing, the tie 80 cords 22 and 23 are slidably connected to the toe members and the heel loop and act to hold the sandal securely in position on the foot of the wearer.

The cords 18, 19, 20, 21, 22 and 23 are 85 preferably of some fibrous material, but obviously such cords can be of any desired material without departing from the spirit of the invention. Also, the heel loop 16 is ordinarily of fibrous material, but may be 90 made of any material desired. The ring 17 may be of any material, but preferably is of resilient material, such as rubber, as it has been found that such material adds to the efficiency of the sandal. 95

Having thus described my invention, what I claim and desire to protect by Letters Patent is:

1. A sandal comprising a combined sole and heel member of resilient material and 100

cork, a toe member comprising a ring member and a plurality of loops of cord having their ends attached to spaced points on the sole and heel member and passing through
5 the ring member, a heel loop having an end secured to each side of the heel end of the combined sole and heel member, and means secured to the instep portion of the combined sole and heel member and passing
10 through said ring member and heel loop whereby the sandal may be attached to the foot of a wearer.

2. A sandal comprising a combined sole and heel member of resilient material and
15 cork, a toe member comprising a ring member and a plurality of loops of cord having their ends attached to spaced points on the sole and heel member and passing through the ring member, a heel loop of
20 cord having an end secured to each side of the heel end of the combined sole and heel member, and tie cords each having one end secured to the instep portion of the combined sole and heel member and passing through
25 said ring member and heel loop and adapted to have their other ends secured together whereby the sandal may be attached to the foot of a wearer.

3. A sandal comprising a combined sole and heel member of resilient material and cork, a toe member comprising a ring member and a plurality of loops of cord having their ends attached to spaced points on the sole and heel member and passing through
35 the ring member, a heel loop of cord having an end secured to each side of the heel end of the combined sole and heel member, and tie cords, one on each side of the combined sole and heel member, and each having one
40 end secured to the instep portion of the combined sole and heel member and passing through said ring member and heel loop and adapted to have the free ends secured together whereby the sandal may be attached to the foot of a wearer.

Signed at Naugatuck, county of New Haven, State of Connecticut, this 3rd day of July, 1931.

HENRIETTA PORR MANVILLE.
